EMBROIDERED FABRIC

Filed June 25, 1938

FIG. 1.

FIG. 2.

INVENTOR

Joseph Picirilli

UNITED STATES PATENT OFFICE

110,979

DESIGN FOR AN EMBROIDERED FABRIC

Joseph Picirilli, New York, N. Y.

Application June 25, 1938, Serial No. 78,070

Term of patent 3½ years

To all whom it may concern:

Be it known that I, Joseph Picirilli, a citizen of the United States of America, residing in New York city, in the Borough of Manhattan, county and State of New York, have invented a new, original, and ornamental Design for an Embroidered Fabric, of which the following is a specification, reference being had to the accompanying drawing, forming part thereof, wherein,

Figure 1 is a plan view of a piece of embroidered fabric showing my new design. The dot and dash lines on the drawing outline substantially a design unit, which unit is repeated in

regular succession as indicated by the extensions beyond the unit boundaries.

Figure 2 is a view of the fabric shown in Figure 1 illustrating an end view of one of the elements constituting the design.

The design is characterized by an embroidered stem portion embodied in the fabric background from which radiates a plurality of loose end threads of contrasting color.

I claim:

The ornamental design for an embroidered fabric, substantially as shown and described.

JOSEPH PICIRILLI.
